COMBINED CONDIMENT DISPENSER SET AND HOLDER THEREFOR

Severns Hilton, Wilton, Maine, assignor to Menschik-
Goldman Company, New York, N. Y., a partnership

Application July 17, 1956, Serial No. 42,278

Term of patent 3½ years

(Cl. D44—22)

Fig. 3.

Fig. 4.

Fig. 5.

Fig. 1 is a perspective view of a combined condiment dispenser set and holder therefor showing my new design;

Fig. 2 is an exploded rear perspective view;

Fig. 3 is a front elevation;

Fig. 4 is a top plan view; and

Fig. 5 is a side elevation.

Corresponding parts throughout are lined and stippled to indicate color contrast.

I claim:

The ornamental design for a combined condiment dispenser set and holder therefor, substantially as shown and described.
